ATTORNEY

UNITED STATES PATENT OFFICE.

HYLDA M. BAKER, OF AERTHERTON, CALIFORNIA.

DESIGN FOR A TOY ANIMAL.

57,299.

Specification for Design. Patented Mar. 15, 1921.

Application filed March 11, 1920. Serial No. 365,074. Term of patent 3½ years.

To all whom it may concern:

Be it known that I, HYLDA M. BAKER, a subject of the King of Great Britain, residing in the city of Atherton, county of San Mateo, and State of California, have invented a new, original, and ornamental Design for a Toy Animal, of which the following is a specification, reference being had to the accompanying drawings, forming a part thereof.

Fig. 2 is a view in front elevation of a toy animal showing my new design.

I claim:

The ornamental design for a toy animal, as shown.

HYLDA M. BAKER
